UNITED STATES PATENT OFFICE.

EDGAR J. MYERS, OF SALT LAKE CITY, UTAH.

RUG-HANDLING MACHINE.

Application filed November 4, 1924. Serial No. 747,798.

To all whom it may concern:

Be it known that I, EDGAR J. MYERS, a citizen of the United States, residing at Salt Lake City, in the county of Salt Lake and State of Utah, have invented certain new and useful Improvements in Rug-Handling Machines, of which the following is a specification.

My invention relates to rug handling machines and has for its object to provide a new and useful means of handling rugs.

A further object is to provide an apparatus for suspending and handling rugs and other similar articles for drying after they have been cleaned, a still further object is to provide an apparatus by which rugs and other similar articles may be suspended for separate display or inspection.

These objects I accomplish with the device illustrated in the accompanying drawings in which similar letters and numerals of reference indicate like parts throughout the several views and as described in the specification forming a part of this application and as pointed out in the appended claims.

In the drawings of which I have shown the best and most substantial embodiment of my invention Figure 1 is a side elevation of the apparatus with a rug suspended thereon. Figure 2 is a plan view of the tracks forming a part of my apparatus and showing manner of using the apparatus. Figure 3 is an enlarged detail showing one end of the apparatus with a fragmentary view of a rug partially raised and suspended for engagement with the carriage. Figure 4 is an end view of the socket. Figure 5 is a plan view of one end of the carriage and Figure 6 is a plan view of the tracks and a switch therefor.

Referring to the drying use of my apparatus, it is desirable to provide some mechanical means by which moist rugs may be easily suspended for drying to prevent creasing or wrinkling and for rapid handling or movement from the cleaning room to the drying room and to the delivery room and with the object of economizing in the floor space required. These objects are accomplished with the present invention which consists of two coacting and spaced sockets A each of which is slotted from one end to receive the roller B on the rod C from which the rug R is suspended. The said sockets are preferably given a cylindrical

form and are open at one end and closed at the other end, and are slotted on their under sides from the open end 1, with a slot 2. The closed end has a central opening 3 through which the rope 4 is passed and knotted, as shown in Figure 4, and a ring 5 is fastened on the side of each of said sockets in which the block and tackle D is secured. A pulley wheel or roller B is fastened to and secured on a rod or pole C from which the rug is suspended, and one of said rollers is operated within each of said sockets A, with the bearings slidable within the slots 2. The bearing standard 70 of each of said wheels B has a swivel joint whereby the said wheels may be secured, and with its pulley in each socket, as shown in dotted lines in Figure 3, it may be turned on said swivel in any horizontal direction 75 to adjust the travel of the pole in the tracks. The said sockets A, when raised to the plane of the track, are closely fitted to one end of the track and form a part thereof. The major portion of the track G is cylindrical in form having a longitudinal slot 80 in its lower side and conforming in shape and size with said sockets A and with the slots of the socket and track in alignment. The track is supported by the U-shaped 85 clamps 6, which are spaced at intervals and are rigidly secured in the upper part of the room. At the ends of each track are guide members 7 which are inverted U-shaped and each of which receive one of 90 said sockets A when the socket is raised parallel with the track. In one end of each guide member is an inclined portion 8 shown in dotted lines in Figure 3 and in plan view in Figure 5. Other portions 12 of the same 95 end of said guide member are curved inwardly, and form the end closure for said member 7. Other portions 11 of the same end of said guide member are rigidly secured to the frame reach 9 to support the 100 said member 7 with the opposite end of each of said guide members supported by the contiguous ends of the track G. The purpose of the inclined portion 8 of said 105 guide member 7 is to move the socket member longitudinally therein toward the end of the aligned track when the socket is raised into the guide member. A longitudinally disposed slot 10 is cut in the upper side of the said guide member 7 to allow the 110 operation of the block and tackle D there-through.

I have shown in Figure 2 an arrangement of tracks for moving the rugs from the cleaning room H through the drying room I and into the delivery room J. As will be obvious any arrangement of rooms and tracks may be used. Any suitable switch, as the one shown in Figure 6, may be used for diverting the rugs or other articles to any desired track.

10 The pole C has short hooked pins 15 secured in the top of the said pole with the said roller bearing B offset from one side of the pole.

15 The operation of my apparatus is as follows:—

After the rug or other article has been cleaned in the room H and while it is still moist, it is secured on the pole C by engaging the edge on the hooked pins 15, or

20 if the article is large it may be doubled over a pole without the pins being used. Two of said sockets A are then slipped over the pulley wheels B of the pole, one on each end with the open end of each in the same

25 direction, and with the block and tackle suspended from the ceiling, or rafter above the ceiling, of the room the tightening of the tackle will hold said sockets on said pulley wheels B and by continuing the 30 longitudinal pull on both tackles at the same time, the rug is raised vertically edge-wise from the floor or table on which it is cleaned. By manipulating the rope 4 the sockets A may be directed into the guide

35 members 7 and the inclined position of the portions 8 of said members 7 will cause the said sockets A to bear end to end against the track G. One of said sockets A may be engaged with one track while the other 40 socket A may engage with a parallel track. The rug, and pole on which it is suspended, may then be moved longitudinally endwise, with the rollers within the track G, to the room I. If curves are provided in the

45 tracks as shown in the room I the rug and pole may be moved laterally through the drying room I, or may be dried in the room I with the drying element F therein and

may then be moved endwise into the delivery room J, as shown in Figure 2. With 50 any suitable switch, as that shown in Figure 6, the track G may be set at any desired angle.

Having thus described my invention I desire to secure by Letters Patent and 55 claim:—

1. A rug handling machine comprising a rug supporting pole; spaced apart wheels secured near the ends of said pole; tracks on which said wheels are operated; socket members adapted to engage the ends of said pole when raising and lowering the rugs; guide members within which said socket members are carried when they are on the plane of said tracks; and an inclined portion of each of said guide members to move said socket members longitudinally against the end of said track.

2. A rug handling machine comprising a pole on which a rug is manually engaged, 70 spaced rollers pivotally secured on said pole, socket members having a slot in the wall thereof and in which said rollers are carried, an elevated tubular track having a longitudinal slot in its under side in which 75 said rollers are operated, inverted U-shaped guide members in which said sockets may be suspended to direct said rollers from the sockets to the track and a block and tackle engaged with each socket to raise said pole 80 and rug and suspend the same from the track.

3. A rug handling machine comprising elevated tracks; a pole from which rugs may be suspended; roller wheels secured 85 near the ends of said pole; socket members adapted to be engaged with said pole when raising and lowering the rugs; means to raise and lower said socket members; and a switch to change portions of said tracks and 90 thereby direct and support said pole in different rooms.

In testimony whereof I have affixed my signature.

EDGAR J. MYERS.
